UNITED STATES PATENT OFFICE.

WARREN R. WALKER, OF NEW DORP, NEW YORK, ASSIGNOR TO COOPER HEWITT ELECTRIC COMPANY, OF HOBOKEN, NEW JERSEY, A CORPORATION OF NEW JERSEY.

SWITCH MOUNTING.

Application filed October 1, 1924. Serial No. 741,081.

My present invention relates to electric switches of the liquid flow type and particularly to a mercury switch having a sealed vitreous envelope and to a means for supporting and for protecting the envelope and for making electrical connections to the switch terminal.

It is an object of my invention to provide a mounting bar for a mercury switch which 10 bar acts as a protecting means for the glass of the switch, as a means for pivotally or otherwise mounting the switch, and as a means for supporting the switch electrode connecting terminals.

15 It is a further object of my invention to provide connecting terminals for the switch which serve also as a means for mounting the switch envelope to the mounting bar.

It is also an object of my invention to 20 provide means for further protecting the switch envelope and its parts.

Further objects of my invention will appear from the specification and drawings.

In the drawings which form a part of this 25 application:

Fig. 1, is a front elevation view of the switch bar unit of my invention, in which the terminal straps of the switch are employed for mounting the switch to the bar by 30 means of studs and nuts which are used also for binding posts for suitable leads to the switch unit,

Fig. 2, is a similar view of the device of Fig. 1, provided with a tubular protecting 35 jacket about the switch envelope which is held in its position thereon by being held against the bar by the terminal straps.

Fig. 3, is a sectional view along the line 3-3 looking in the direction of the arrows, 40 and

Fig. 4, is a perspective view of the envelope protecting jacket.

In the drawing the bar 1 carries at each end the studs 2-2 which by means of the nuts 45 3, 3 hold the straps 4, 4 of switch 5 against the ends of bar 1. On the ends of switch envelope 5 the caps 6, 6 make electrical contact between the electrodes 7 and 8 thereof and their respective straps 4, 4 which latter are 50 connected to said caps 6, 6 as by soldering, brazing, or welding. The nuts and washers

9, 9 and 10, 10 serve for making electrical contacts from suitable leads.

In Figs. 2 and 3 are shown a jacket 14 protecting sleeve 14 mounted about the envelope 5 and held between said envelope and said bar 1 by means of the said straps 4, 4. At one end the tubular jacket has been cut transversely and longitudinally to form the depending guards 15-15 which extend downwardly on either side of the bulb 10 of the envelope 5. A slot 17 is provided in the upper part of the jacket for the seal-off tip 18 of envelope 5, the counterbore 19 being formed in bar 1 for the positioning of said seal off therein. Fig. 4 shows the jacket 14 separated from the switch unit and shows details of the guards 15 and said slot 17.

In the use and operation of my invention mechanical connection is made by bar 1 to 70 suitable mounting means and to tilting or shifting means for causing movement of the mercury in the switch for the opening and closing of the circuit therethrough. A method and means of mounting and using and operating the switch-bar unit of my invention 75 is shown and described in my copending application Serial Number 741,080 patented February 7, 1928, Number 1,658,619 to which reference is hereby made.

I claim—

1. A switch unit comprising a mercury switch having a vitreous envelope and electrodes sealed therethrough, a bar of insulating material coextensive longitudinally with 85 said envelope, screw studs in the ends of said bar, straps mounted to the ends of said envelope, electrically connected to the leads thereof and mounted to said screws to hold said envelope to said bar, nuts and washers 90 on said screws for holding said straps and for connecting line leads thereto.

2. A switch unit comprising a mercury switch having a vitreous envelope and electrodes sealed therethrough, a bar of insulating material coextensive longitudinally with 95 said envelope, screw studs in the ends of said bar, straps mounted to the ends of said envelope, electrically connected to the leads thereof and mounted to said screws to hold said envelope to said bar, nuts and washers 100 on said screws for holding said straps and for

connecting line leads thereto and a protecting jacket held on said envelope by said straps and cap.

3. A switch unit comprising a mercury switch having a vitreous envelope and electrodes sealed therethrough, a mounting member extending longitudinally with said envelope, straps fused to conductors on the ends of said envelope electrically connected to the

electrodes thereof and mounted to said 10 mounting member by screw threaded members adapted for attaching connector leads to said switch through said straps.

Signed at Hoboken in the county of Hudson and State of New Jersey this 29th day 15 of September, A. D. 1924.

WARREN R. WALKER.
